UNITED STATES PATENT OFFICE.

MOSES COHEN, OF NEW YORK, N. Y.

SUSPENDERS.

986,362.

Specification of Letters Patent. Patented Mar. 7, 1911.

Application filed June 4, 1908. Serial No. 436,621.

To all whom it may concern:

Be it known that I, MOSES COHEN, a citizen of the United States, residing at the city of New York, in the county of New York, 5 and State of New York, have invented certain new and useful Improvements in Suspenders, of which the following is a specification.

My invention relates to suspenders of the 10 sliding back type which are designed to yield freely with the movements of the wearer and my objects are to produce the suspenders in such manner that they will permit the utmost freedom of motion with 15 a minimum of friction and wear thereby promoting the comfort of the wearer and prolonging the life of the suspenders.

I attain my objects in the manner illustrated in the accompanying drawing in 20 which—

Figure 1 is an elevation of my improved suspender back; Fig. 2 an edge view, partly in section on the line 2—2 of Fig. 1; Fig. 3 a view of a sliding strap opened to show 25 the reinforcing strap; Fig. 4 a sectional view on the line 4—4 of Fig. 3.

My suspenders comprise the usual shoulder straps 1 and 2 and in order that they 30 may slide freely with the motions of the wearer I do not rigidly secure them together where they meet in the back but make a sliding connection. This sliding connection is obtained, together with a swinging or 35 swivel motion, between the shoulder straps and the short strap 6 by using a two part metal trimming the upper member 3 of of which is provided with two parallel slots and the lower member 4 with a single slot normally parallel to the two slots in the 40 upper plate. A stud 5 connects the two members and forms a swinging or swivel joint.

A strap 6 is secured in the slot of the lower member 4 and carries the usual means for 45 attaching the suspenders to the back of the trousers. (Not shown). Rollers 7 and 8 are secured to the tops of the slots in the

upper member 3 to reduce friction. A first strap 9 and a second strap 10 are secured to the ends of the shoulder straps 1 and 2 and 50 pass, one through the lower slot and one through the upper slot, as shown in Fig. 2, working against the rollers 7 and 8. One strap is slightly longer than the other so that the finished suspenders will be symmetrical. This construction permits one shoulder strap to lengthen or shorten with respect to the other when the shoulders of the wearer are raised and lowered. The 55 swivel joint made by the stud 5 accommodates the side to side motions of the back of the wearer.

In order that the wear of the straps passing through the slots may be reduced to a minimum without unduly increasing the 60 bulk of the suspenders I secure a reinforce 65 11 on the inside of the strap 9 by pasting, gluing, cementing or any other suitable means. This reinforce is smaller than the strap and is skived or "feather-edged" all 70 the way around as shown in Figs. 2 and 4 so that it cannot catch in the slot in sliding through, and, as it is skived at the edges and does not come to the edge of the strap it reinforces is invisible when the suspenders are made up. The strain is transferred 75 from the edges to the middle part of the strap and the life of the suspenders is greatly prolonged. The other strap 10 has 80 a like reinforce 12.

In order that there may be no buckling or wrinkling of the sliding strap in the finished suspenders I prefer to use a form or die when pasting so that the straps when dry will have the required U-shape indicated in 85 Fig. 2.

I claim:—

A suspender back comprising a pair of shoulder straps; a pair of slide straps secured to the front and back of the ends 90 of the shoulder straps; a plate provided with two slots, one of said slide straps passing through an upper slot and the other through the lower slot therein; a reinforce strap

smaller than the slide strap provided with
a skived edge secured to each of said slide
straps where it contacts with the slots; a
second slotted plate; a stud swingingly con-
necting the two plates; and a strap at-
tached to the slot in the lower plate adapted
to be secured to the garment to be supported.

In testimony whereof I have affixed my
signature in presence of two witnesses.

MOSES COHEN.
